(57) CLAIM

The ornamental design for a trailer body, as shown and described.

DESCRIPTION

FIG. 1 is a top, front, and left side perspective view of a trailer body embodying our new design;

FIG. 2 is a top, rear, and left side perspective view thereof;

FIG. 3 is a left side elevation view thereof;

FIG. 4 is a right side elevation view thereof;

FIG. 5 is a front elevation view thereof;

FIG. 6 is a rear view thereof;

FIG. 7 is a top plan view thereof;

FIG. 8 is a bottom plan view thereof;

FIG. 9 is a top, front, and left side perspective view thereof with door and trunk panels opened; and,

FIG. 10 is a top, rear, and left side perspective view thereof with the door and trunk panels opened.

The broken lines in the drawings illustrate portions of the trailer body and environmental trailer structures that form no part of the claimed design.

1 Claim, 10 Drawing Sheets
